UNITED STATES PATENT OFFICE.

JOHN H. PATTERSON, OF THE UNITED STATES ARMY.

CAR-COUPING.

SPECIFICATION forming part of Letters Patent No. 257,974, dated May 16, 1882.

Application filed February 28, 1882. (Model.)

To all whom it may concern:

Be it known that I, JOHN H. PATTERSON, an officer in the army of the United States, stationed at and residing at the military post of 5 Fort Wallace, Kansas, have invented a new and useful Safety Car-Coupler, of which the following is a specification.

Figure 1 is a perspective view of the complete device; Fig. 2, a similar view of link to 10 be used with it.

My invention relates to improvements in car-couplers whereby the present necessity of train-men remaining between the cars when making couplings is obviated. I attain this object by 15 the mechanical means which a view of accompanying drawings and model will make plain, claiming for this invention simplicity of construction, durability, and trifling cost.

I describe my invention as consisting of a 20 link-prop, A, a pin-prop, B, a steadier, C, and a closed link, D—i. e., one with pin-hole at one end. The office of the link-prop is to maintain the link a little above a horizontal line when extended for entering draw-head other than the one to which it is attached. The purpose of the pin-prop is to maintain the pin in a 25 vertical position, the point of pin just entering pin-hole. It remains in this position until forced back by pressure on its accompanying link-prop.

The size of the link-prop is conditional only 30 upon the size of the draw-head to which it is to be attached. The size of the pin-prop the same, though the distance of its cross-bar above top of draw-head depends upon the length of pin from flange to point. The purpose of the steadier is to hold head of pin from being drawn over 35 by pin-prop when it is forced back, thus insuring a vertical dropping of the pin. The link is closed at one end—that is, with simply pin-hole 40 through it, the hole in link large enough to admit free movement of link. The purpose of this form of link is to prevent link from being forced back where the friction in entering draw-head other than the one where it is already 45 made fast is sufficient to overcome the inertia of the link.

The details of the act of coupling I thus describe: One end of the link being already pinned, the link-prop is drawn up and the link, 50 drawn out to its full extent, placed upon it. The link projects far enough beyond its link-prop to pass pin-hole in draw-head, where it is to enter before pin drops, the direction of the link being just above the horizontal line. It often

happens that the draw-heads are not upon the 55 same horizontal line. In such case the link is first inserted and pinned in the higher draw-head. The link resting on bottom of draw-head *a*, to which it is made fast, will enter opposite draw-head, *b*, anywhere from bottom to 60 top, according to height of bottom of draw-head *a* above bottom of draw-head *b*. When the bottom of one draw-head is above the top of its opposite, then of course the coupling cannot be made with the straight link—a continuity 65 not likely to occur, cars now being made of a standard height. The pin-prop on the car to which the attachment is to be made is raised until the depression in cross-bar is directly over pin-hole. This throws its accompanying link-prop to the front. The head of the pin is placed in the steadier, the flange in the depression, and the pin remains for the time in suspension. The car can be moved without disturbing the 70 perpendicularity of the pin. As the cars come together the link-props meet and, yielding to light pressure, pass underneath their respective draw-heads, the pin-prop is thrown back, the pin falls, and the coupling is complete. To prevent, where draw-heads are of different 75 heights, one link-prop passing over the other, a piece of metal is attached to cross-bar of each link-prop, extending below it. This insures the link-props striking.

The steadier can be utilized to draw pin by 80 passing a cord through its top as a fulcrum, cord attached to head of pin. This requires a brace to steadier across draw-head and near its top, attached of course to draw-head. This invention is applicable to present form of draw-heads in general use, being attached by two 85 bolts on each side of a draw-head, and can be fabricated and attached at any forge by any blacksmith.

What I claim is—

1. In combination, the pivotal abutting link-lifter A and pin-holder B, united by the link D, as shown and described, and for the purpose set forth.
2. In a car-coupling, the link-guide A, pin-support B, link-bars D, and pin-guide C, substantially as shown and described.

JNO. H. PATTERSON,
Captain 20th Infantry.
